(57) **CLAIM**

The ornamental design for a decorative brushed steel scissor-shaped base for furniture, as shown and described.

DESCRIPTION

FIG. 1 is a front view in elevation of a decorative base for furniture showing my new design with a drawer chest;

FIG. 2 is a rear view in elevation thereof;
FIG. 3 is a right side view in elevation thereof;
FIG. 4 is a left side view in elevation thereof;
FIG. 5 is a top view in plan thereof;
FIG. 6 is a bottom view in plan thereof;
FIG. 7 is a front view in elevation of a decorative base for furniture showing my new design with an armoire;
FIG. 8 is a rear view in elevation thereof;
FIG. 9 is a right side view in elevation thereof;
FIG. 10 is a left side view in elevation thereof;
FIG. 11 is a top view in plan thereof;
FIG. 12 is a bottom view in plan thereof;
FIG. 13 is a front view in elevation of a decorative base for furniture showing my new design with a night stand;
FIG. 14 is a rear view in elevation thereof;
FIG. 15 is a right side view in elevation thereof;
FIG. 16 is a left side view in elevation thereof;
FIG. 17 is a top view in plan thereof;
FIG. 18 is a bottom view in plan thereof;
FIG. 19 is a front view in elevation of a decorative base for furniture showing my new design with a buffet;
FIG. 20 is a rear view in elevation thereof;
FIG. 21 is a right side view in elevation thereof;
FIG. 22 is a left side view in elevation thereof;
FIG. 23 is a top view in plan thereof;
FIG. 24 is a bottom view in plan thereof;
FIG. 25 is a front view in elevation of a decorative base for furniture showing my new design with a dresser;
FIG. 26 is a rear view in elevation thereof;
FIG. 27 is a right side view in elevation thereof;
FIG. 28 is a left side view in elevation thereof;
FIG. 29 is a top view in plan thereof; and,
FIG. 30 is a bottom view in plan thereof.
The broken lines shown throughout are for contextual illustrative purposes and form no part of the claimed design.
